UNITED STATES PATENT OFFICE.

GEORGE JOHN LOVELL, OF NEW YORK, N. Y.

PACKAGE.

1,413,412.

Specification of Letters Patent. Patented Apr. 18, 1922.

Application filed July 9, 1920, Serial No. 395,048. Renewed September 15, 1921. Serial No. 500,968.

To all whom it may concern:

Be it known that I, GEORGE J. LOVELL, a subject of the King of Great Britain, and resident of the city of New York, borough 5 of Manhattan, county of New York, and State of New York, have invented a new and Improved Package, of which the following is a full, clear, and exact description.

My invention relates to a package, and 10 more particularly that type of package primarily designed with a view of permitting of the transportation of phonograph records and similarly perforated discs.

In connection with shipping records, it is 15 a well appreciated fact that a great amount of breakage occurs despite the fact that the same are packed with great care. This is to be attributed to the extremely rough usage which packages receive in both parcels post 20 or upon being shipped by express.

Further, a great amount of time has necessarily been involved in packing records, which to say the least, are of a cumbersome nature, and extremely fragile.

With this in view, I have invented a package more particularly adapted for use in connection with phonograph records, by means of which the records may be quickly packed, and the danger of breakage during 30 shipment reduced to a minimum.

It is further well understood that numerous losses during shipment occur, in connection with records in packages which have been heretofore used, for the reason that it 35 has been possible to readily extract a number of records without the loss being apparent upon the package being received.

Having this defect also in mind, I have 40 constructed a package, which further shall incorporate means whereby any tampering which the same has become subjected to will become apparent instantly.

Reference is had to the attached sheet of drawings which illustrate one practical embodiment of my invention, and in which 45 drawings,

Figures 1 and 2 illustrate the inner faces of the side members forming the package, and prior to their assemblage.

Figure 3 shows a package in section, in 50 process of being assembled.

Figure 4 is a similar view, but showing the parts assembled and housing a record disk.

Figure 5 is an exterior view of a package, and

Figures 6 and 7 show details of my invention.

In these views the reference numeral 10, designates sheets of any suitable material, which material preferably includes resilient qualities, such as are incorporated in corrugated board. Each of these sheets are formed with a centrally disposed opening 11, above and below which are slots 12 which are provided for a purpose hereinafter more 65 fully specified.

In forming the complete package, and associating therewith the record or records to be shipped, a ferrule is inserted through one of the centrally disposed openings.

Referring now more particularly to Figure 7 it will be seen that this ferrule conveniently includes a cylindrical body portion 13, which has its ends split, as has been indicated by the reference numeral 14 whereby the end portions of the ferrule may be turned up to provide radially extending lugs 15. One end of the body portion 13 is now flattened so as to provide lugs 15, and the opposite end thereof is inserted through the 80 opening 11 of one of the sheets 10.

Subsequent to this, a strip 16 formed with a gummed portion 17 adjacent its ends is caused to overlie the lugs 15, the gummed ends of the strip being moistened and threaded through the slots 12 so that the ferrule is virtually anchored in place, in that any withdrawal of the same from the opening 11 will be immediately apparent, due to the fact that the strip 16 will have become broken.

A record 18 may now be associated with the ferrule 13 the turn table opening of the record being utilized for this purpose, as has been clearly shown in Figure 3. If but one record is to be shipped, the second sheet 95 10 may now be threaded on to the ferrule subsequent to which the split end of said ferrule is spread so as to provide the lugs 15 adjacent this end, whereby to prevent any movement of the parts relative to one another.

After this has been accomplished, a second strip 16, which has been transversely applied to the sheet 10, as has been shown in Figure 3, is slipped through the slot 12 so as to 105 cover the last named end of the ferrule, and

to provide a seal which shall immediately indicate any tampering to which the package may have been subjected.

It is obvious that any desirable number 5 of records might be shipped in this manner, by simply providing a ferrule with longer body portions 13, and utilizing additional sheets of material 19, which conveniently embody resilient qualities, these latter sheets 10 being interposed between the faces of adjacent records.

From the foregoing, it will be appreciated that I have constructed a package by means of which danger of breakage in shipping 15 records is reduced to a minimum, any suitable number of records being capable of being shipped in a package.

The foregoing is to be attributed to the fact that the edges of the records or other 20 members housed within my improved type of package are completely protected so that danger of the same being struck in handling is eliminated.

It will further be understood that means 25 has been provided in a package constructed in accordance with my invention, which shall prevent any tampering with the contents of the same, without this tampering becoming immediately apparent upon receipt 30 of the package.

Obviously numerous modifications of

structure might readily be resorted to without in the least departing from the spirit of my invention.

Having thus described my invention, what 35 I claim as new and desire to secure by Letters Patent is as follows;—

1. A package, including a pair of sheets of material, said package being adapted to receive a record interposed between said 40 sheets, said sheets being formed with openings adapted to align with the turn table opening of a record, and means passing through all of said openings for retaining the parts in assembled position, and strips 45 of material extending through slots formed above and below the openings in said sheets and to overlie such retaining means whereby it will be necessary to sever said strips prior to an opening of the package. 50

2. A package, including a pair of sheets of material, said package being adapted to receive a record interposed between said sheets, said sheets being formed with openings adapted to align with the turn table opening 55 of a record, retaining means passing through said openings for retaining the parts in assembled position, and a sealing means co-operating with said retaining means and having certain of its portions inaccessible 60 from the exterior faces of said sheets.

GEORGE JOHN LOVELL.
